DESIGN FOR A CAMERA

Chester W. Crumrine, Rochester, N. Y., assignor to Eastman Kodak Company, Rochester, N. Y., a corporation of New Jersey

Application November 19, 1938, Serial No. 81,237

Term of patent 7 years

To all whom it may concern:

Be it known that I, Chester W. Crumrine, a citizen of the United States of America, residing at Rochester, in the county of Monroe and State of New York, have invented a new, original, and ornamental Design for Cameras, of which the following is a specification, reference being had to the accompanying drawing, forming a part thereof, in which—

Fig. 1 is a perspective view of a camera showing my new design.

Fig. 2 is a front elevation of the camera shown in Fig. 1.

Fig. 3 is a side elevation of the camera shown in the preceding figures.

I claim:

The ornamental design for camera, as shown.
CHESTER W. CRUMRINE.
